UNITED STATES PATENT OFFICE

THOMAS PARKINSON, OF PENDLETON, MANCHESTER, ENGLAND

APPARATUS FOR THE LIQUID TREATMENT OF TEXTILE FABRICS

Application filed January 9, 1929, Serial No. 331,368, and in Great Britain January 13, 1928.

The invention relates to apparatus for the liquid treatment of textile fabrics, and of a type used in connection with dye becks for piece goods, consisting of roller-provided vessels or becks pivoted at their extremes upon a frame movable in circular manner about a common axis, and whereby said becks may take up different positions relatively to the cloth transmission roller revolvably mounted external of said becks.

In this type of apparatus, one vessel may be employed, for example, for dyeing purposes, and another afterwards brought into position for washing purposes. One vessel only at a time is usually capable of being in use, and the object of my present invention is to provide means whereby operations of greater number are capable of being attained with the apparatus in any one period, and a number or variety of fabrics or material treated at once or together.

According to my invention, I provide one at least of the vessels employed in multiple-compartment form, one of said compartments being, preferably, a longitudinal continuation of the other, and divided therefrom by a partition. On the other hand, a second and undivided vessel, separately pivoted, or like the first-named movable about said pivots at the ends, and both movable about an external or common axis provided, is preferably employed.

Separate rollers are preferably used for transmitting the material to each compartment of a divided vessel referred to, said rollers being capable of independent control or movement.

With reference to the accompanying drawings, illustrating one form of my invention applied to apparatus suitable for dyeing and like operations, Fig. 1 is an end elevation of certain parts of the apparatus, but broken away at the middle portion in order to show clearly a pair of dye becks in two positions, in the one case, as represented by full lines, and in the other case by broken lines.

Fig. 2 is a portion of Fig. 1, but on a reduced scale, and relative to one position of the becks above referred to.

Fig. 3 is a front elevation of one end por-

tion of the apparatus at right angles to Fig. 1, and Fig. 4 is a similar view of the opposite end portion thereof.

Fig. 5 is a middle portion of the apparatus between the two end-portions last named, only so much being shown, however, as to make the explanation clear.

a is the main framing of the apparatus, dye becks therefor being indicated at *b*, *c* and *d*. Of these, *b* and *c* are compartments of one vessel, according to my invention, a dividing partition being shown at *e* (Fig. 5) but *d* is continuous from end to end. The becks are all pivoted at their ends by means of trunnions *h* revolute in supporting heads *k* of arms *k*, the latter capable of rotation about a common axis, or that of shaft or pipe *m*.

The centres of gravity of the becks or vessels named being arranged below the points of their suspension, ensures said vessels always remaining in position with their openings uppermost. The hollow shaft *m* is revolutely mounted in the main framing *a*, and is here used for the conveyance of steam to pipe connections *n*, the latter in communication with the various becks through passages provided in the heads *k* and trunnions *h*. The usual means for distribution of this steam within the becks is not shown, to prevent confusion. *o* is a valve-controlled steam pipe for supply of steam referred to. Bosses *r* of arms *k*, and whereby the latter are attached to shaft *m*, are also in attachment with pipes *n* by means of hollow T couplings *t*, and said bosses and T couplings are internally capable of allowing steam to pass from *m* to *k* and thence to the beck concerned, in each case. *u* are steam-control valves for pipes *n*.

Worm-wheel gearing is shown at *s*, capable, by means of hand wheel indicated, (Fig. 3) of being used to revolve shaft *m*, and thus make the becks turn about the common axis of said shaft, when change of position of the latter vessels is desired or required.

As indicated in Fig. 2, the position is such that the fabric *v* under treatment is capable of passing from one beck to the other provided, and after leaving transmission

5 roller w and before reaching the other roller x . For example such an arrangement would be suitable for the fabric or material being dyed in the one beck, and passed into the other for washing purposes, in a continuous manner, and without the need, as heretofore, of changing over the becks and re-arranging the fabric or material accordingly.

10 With reference to Fig. 5 and relatively to Figs. 3 and 4, it will be seen that the position or arrangement is such that two pieces of fabric y and z are capable of separate treatment in the dual-compartmental vessel, forming becks c and b respectively.

15 The usual revoluble rollers I are shown within these becks and that marked d , but other details requisite are not included, as forming no part of the present invention.

20 In the case of Fig. 5 it will be seen that the transmission rollers consist of two, marked x and x_1 the one being capable of independent drive to the other. That is to say, the revoluble shaft 2 in bearings within the frame a , and driven through gearing 3, 25 is provided with a member such as indicated at 4 (Fig. 4) the sliding movement of which along shaft 2 connects roller x_1 with said shaft 2. Details of this member are omitted as not being necessary.

30 It will be seen however, that when one transmission roller is being positively driven to draw the fabric or material out of the last beck used in the process, the other transmission roller is largely unrestrained, and so 35 permits of the movement of the whole piece or material. Means for putting tension upon said cloth or material during said movement, and by the use of a braking device, for instance, at the otherwise unrestrained roller 40 named, may be used, but is not indicated since it does not form part of this invention.

I claim:—

45 1. In dyeing apparatus for the liquid treatment of textile fabrics, having becks pivoted at their ends upon a frame capable of movement in a circular manner about a common axis, the provision of one or more steam-heated becks each divided into separate compartments for the purpose herein set forth.

50 2. In dyeing apparatus for the liquid treatment of textile fabrics, having becks pivoted at their ends upon a frame capable of movement in a circular manner about a common axis, an upper beck divided into separate compartments, steam inlets within the trunnion on which said beck is revolvably mounted, a hollow connection to said inlets pivoted on said common axis of turn substantially as herein set forth.

55 60 In testimony whereof I have affixed my signature.

THOMAS PARKINSON.
